CHARLES L. COLE, OF RICHMOND, MICHIGAN, ASSIGNOR TO HIMSELF AND THOMAS JOHNSON, OF SAME PLACE.

Letters Patent No. 84,261, dated November 24, 1868.

IMPROVEMENT IN SPINNING-WHEEL.

The Schedule referred to in these Letters Patent and making part of the same.

To whom it may concern:

Be it known that I, CHARLES L. COLE, of Richmond, in the county of Macomb, and State of Michigan, have invented a new and useful Improvement in Spinning-Wheels; and I do declare that the following is a true and accurate description thereof, reference being had to the accompanying drawings, and to the letters of reference marked thereon, and being a part of this specification.

The object of this invention is to so construct spinning-wheels that the operator may remain seated and stationary, and prevent the necessity of walking towards the spindle, after the yarn is spun, to wind the same. This is done by the mechanism, hereinafter described, operated by treadles, which cause the spindle to advance to and recede from the operator, as desired.

In order to accomplish this end, I construct a proper frame, A, upon which is mounted, by proper standards, B, the driving-wheel C, to which motion is communicated by means of the crank D.

The spindle E is suitably attached to the head F, which, in turn, is secured to the support G, which is fastened to the friction-wheel H, properly secured to the rock-shaft I, upon which are also placed proper pulleys, by means of which and the belts J and K, motion is communicated to the whole from the driving-wheel C.

Another wheel, L, is secured to the rock-shaft M, properly journalled in the frame A, near the position of the operator, when using the machine.

A belt, N, passes over this wheel L, its lower ends being secured to the treadles O and P.

To this rock-shaft M are secured the arms Q and R, to the outer ends of which are journalled the friction-wheels S and T, which are provided with proper pulleys, over which pass the belts U and V, which lead around the shaft which sustains the driving-wheel C, and by which motion is given to said friction-wheels S and T.

To operate this machine, and compel the spindle to advance toward or recede from the operator, as required, it is simply required that the operator shall alternately press his foot upon the treadles, which will partially rotate the rock-shaft M, and compel, alternately, the face of the friction-wheels S and T to engage with the face of the friction-wheel H, which will throw the spindle forward or back, as may be desired.

What I claim as my invention, and desire to secure by Letters Patent, is—

The rock-shaft M, wheel L, friction-wheels H, S, and T, arms Q and R, belts N, U, and V, and treadles O and P, when arranged relatively to each other, as herein described, in connection with any hand-spinning wheel, and operating as and for the purposes substantially as set forth.

CHARLES L. COLE.
